UNITED STATES PATENT OFFICE.

ALOYSIUS G. BLINCOE, OF BARDSTOWN, KENTUCKY.

PENCIL-HOLDING CASE.

SPECIFICATION forming part of Letters Patent No. 734,396, dated July 21, 1903.

Application filed March 23, 1903. Serial No. 149,016. (No model.)

To all whom it may concern:

Be it known that I, ALOYSIUS G. BLINCOE, a citizen of the United States, residing at Bardstown, in the county of Nelson and State 5 of Kentucky, have made certain new and useful Improvements in Pencil-Holding Cases, of which the following is a specification.

My invention is an improvement in pencil-holding cases, especially designed for holding 10 the pencil in the pocket when not in use; and the invention consists in certain novel constructions and combinations of parts, as will be hereinafter described and claimed.

In the drawings, Figure 1 is a side elevation 15 of a case embodying my invention, the pencil being in place therein. Fig. 2 is a longitudinal section of the construction shown in Fig. 1. Fig. 3 is a side elevation of the case contracted to fit a comparatively short pencil. Fig. 4 20 is a side elevation of a somewhat different form of case, and Fig. 5 is a detail view showing a somewhat different construction.

My improved holding-case, as shown in 25 Figs. 1, 2, and 3, includes the upper section A and the lower section B, fitted telescopically together at C, so the sections may slide upon each other to adjust the case to the length of the pencil. The joint C may be made sufficiently tight to hold the sections in any desired 30 adjustment, so that the said sections may be pushed together or drawn apart to fit the pencil and will hold firmly when so adjusted. The upper section A is provided with a spring-clasp or other fastening D to engage the pocket

35 (shown at E) in order to hold the case within the pocket. The clasp D includes an outer jaw, spring-actuated into engagement with an inner jaw to clasp the pocket, as will be understood from Fig. 1 of the drawings. I also provide the section A with springs F, (shown as 40 spring-tongues,) which project into the section and pressing against the pencil G hold the same within the case. The lower section B is provided near its lower end with a conical 45 downwardly-converging portion H and below the same with the tubular extension I, upon which is fitted the removable cap J, which is slipped to place, as shown, or may be threaded upon the tubular extension I, as shown in

50 Fig. 5, or otherwise removably fitted thereon so it can be readily removed whenever it is desired to clean out the lower section B, or for any other purpose. The conical portion H is fitted to receive the sharpened end of the

pencil, while the point G' thereof projects 55 into the tubular extension I, and is thus prevented from breaking.

In Figs. 1 and 2 the holder is shown extended to receive a long pencil, while in Fig. 3 it is contracted to fit a shorter pencil. 60

In the construction shown in Figs. 1, 2, and 3 the lower section is fitted over and upon the upper section A. It will be understood, however, that when desired the upper section may be fitted over the lower section, as shown 65 at K in Fig. 4, and this construction may be preferred in some instances, because by it the lower section of the holder may be caused to fit the pencil more closely, and thus tend to prevent any considerable movement of the 70 pencil at its lower sharpened end within the conical portion and the tubular extension of the lower section of the case.

By my invention it will be noticed the pencil can be carried in the pocket with perfect 75 safety without any danger of the point becoming broken, and means are provided whereby the case can be conveniently adjusted to suit the length of the pencil, and the lower end of the case is covered by a removable cap, as shown and before described, and if the pencil slips through the springs at top it may be pushed up by pushing the lower section up so it can be taken hold of by the upper end. 80

Having thus described my invention, what I claim, and desire to secure by Letters Patent, is—

The pencil-holding case herein described consisting of the sections fitted telescopically 90 and sliding upon each other at their meeting ends, the upper section being provided with a clasp for connection with the pocket and with means for clamping the pencil and the lower section being provided at its lower end 95 with a conical downwardly-converging portion and with a tubular extension below the same and the cap fitting removably on the tubular extension, the conical portion receiving the sharpened portion of the pencil and 100 the tubular extension, the lead or point thereof all substantially as and for the purpose set forth.

ALOYSIUS G. BLINCOE.
